UNITED STATES PATENT OFFICE.

THOMAS SHAFFER PATTERSON, OF STATE COLLEGE, PENNSYLVANIA.

AIR WASHER.

Application filed May 12, 1927. Serial No. 190,838.

The purpose of this invention is to supply pure moist air for humidification in the formation of a gaseous mixture for the operation of internal combustion engines.

5 In practicing the invention air is caused to travel through a body of water, preferably in jets, whereby dust and other impurities are removed and the air humidified and conditioned to produce most advantageous results in a smooth running engine, an increase 10 of power and a material reduction in the deposition of carbon.

While the drawing illustrates a preferred embodiment of the invention, it is to be understood that in adapting the means to meet specific needs and requirements, the design may be varied and such other changes in the minor details of construction may be resorted to within the scope of the invention as 20 claimed, without departing from the spirit thereof.

For a full understanding of the invention and the merits thereof, reference is to be had to the following description and the drawing 25 hereto attached, in which,—

Figure 1 is an elevational view, partly in section, illustrative of an embodiment of the invention.

Figure 2 is a vertical, central, sectional view of the washer.

Figure 3 is a horizontal sectional view on the line 3—3 of Figure 2.

Corresponding and like parts are referred to in the following description and designated in the several views of the drawing by like reference characters.

The numeral 1 designates the radiator and 2 the motor of a mechanically propelled vehicle, such parts being of well known construction and arrangement and illustrated to demonstrate the application of the invention. A tank 3 of suitable capacity and design is associated with the radiator 1 and motor 2, and for convenience, is mounted upon the latter and is formed with an inlet 4 for the inflow of air, and an inlet 5 for the inflow of water from the jacket of the motor, and an outlet 6 for the outflow of the water to the radiator. Collars project from the tank 3 in line with the respective openings 5 and 6 and provide convenient means for coupling the tank to the motor and the radiator, as indicated most clearly in Figure 1. The air inlet 4 is formed in a cover 7 provided to close 50 the top of the tank 3, and a tube in line with and forming the air inlet projects above and

below the cover, as indicated most clearly in Figure 2, and constitutes a guide for an air distributor movable vertically within the tank and controlled by the change of level 60 of the water therein.

The air distributor comprises a stem 8, and a head 9, and is preferably formed of a length of pipe having an end portion coiled to provide the head 9. A plurality of small openings 10 are formed in the top side of the head 9 for the discharge of air in jets. The stem 8 has a loose fit within the tubular air inlet and is directed in its vertical movement thereby. A float 11 has the air distributor connected thereto and is loosely mounted upon the lower portion of the tubular air inlet 4 and is directed in its vertical movements thereby. The head 9 of the air distributor is spaced from the float so as not to obstruct the discharge of the jets of air, while at the same time acting as a spreader to deflect the jets of air laterally to cause every part to come in contact with the water whereby impurities are eliminated. Any suitable means may be 80 employed for connecting the air distributor to the float and, as shown, a clip 12 is employed. A plug 14 closes the lower end of the pipe from which the air distributor is formed and provides convenient means for removing any scale or other accumulation that may collect within the distributor.

The usual overflow pipe 13 associated with the radiator is provided with a check valve 15 which normally closes to prevent air entering the radiator but which is free to unseat to provide an outlet for an excess of water. A pipe 16 leading from the carburetor, not shown, extends into the upper portion of the radiator and conveys the pure moist air therefrom to the carburetor to be mixed with a volatile hydrocarbon whereby to produce the gaseous mixture for operating the motor. It is observed that the tank 3 provides an additional cooling means for reducing the 100 temperature of the water utilized in the cooling system. It also provides means for humidifying the air and removing impurities therefrom. The cool air drawn into the inlet 4 and discharged in small jets into the water 105 contained in the tank 3 is heated, thereby resulting in warm air of an even temperature being supplied to the carburetor which is of advantage in obtaining a gaseous mixture free from liquid particles, with a result of 110 a saving of fuel and a quick combustion with a minimum residue.

Having thus described the invention, I claim:

A water tank adapted to be interposed in the cooling system of an internal combustion engine, a tube projecting above and below the top of the tank to provide an air inlet and guide, an air distributer comprising a perforated head and a stem, the latter fitting

loosely within the said tube, and a float loosely mounted upon the lower end of the said tube and having the air distributer connected thereto for movement therewith and spaced thereabove and serving as a deflector to spread the jets of air.

In testimony whereof I affix my signature.

THOMAS SHAFFER PATTERSON. [L. S.]
